UNITED STATES PATENT OFFICE.

WILHO E. LAHTI, OF WINDSOR, CALIFORNIA.

MUSIC-LEAF TURNER.

Application filed October 3, 1927. Serial No. 223,689.

This invention relates to improvements in means for turning the pages or leaves of books, music or the like.

The principal object of this invention is to provide means whereby pressure upon a foot pedal will accomplish the turning of a page, thereby eliminating the use of the hands.

Another object is to produce a device of this character which may be employed either upon a stand or upon a musical instrument such as a piano.

A further object is to produce a device of this character which is simple in construction and one wherein the parts will not be easily disarranged.

A still further object is to produce a device of this character which is economical to manufacture and one which will be easy to transport from place to place.

Other objects and advantages will be apparent during the course of the following description.

In the accompanying drawings forming a part of this specification, and in which like numerals are employed to designate like parts throughout the same,

Figure 1 is a front elevation of my device partly broken away,

Figure 2 is a detail view showing the position of the operating arms with respect to the arm gear,

Figure 3 is a top plan view taken on the line 3—3 of Figure 4,

Figure 4 is a vertical cross section taken on the line 4—4 of Figure 3,

Figure 5 is an enlarged detail view showing the manner of securing the rack to the device,

Figure 6 is an enlarged fragmentary detail view showing the manner the rack bar operates the floating gear, and

Figure 7 is a side elevation on a reduced scale of my entire device.

When music is being played, either upon a piano or other instrument, it is necessary for the player or an assistant to turn the pages of the sheet music from time to time. This interrupts the player and it is to prevent this disadvantage that I have perfected my present invention which consists in a mechanical device whereby the single pages may be turned when desired through the actuation of a foot lever, or pedal.

In the accompanying drawings wherein for the purpose of illustration is shown a pre-

ferred embodiment of my invention, the numeral 5 designates a box-like structure having a window 6 formed therein. This box-like structure may be positioned upon a supporting base 7 to which legs 8 are secured, or the same may rest directly upon the top of a musical instrument such as a piano.

Positioned within the box-like structure 5 is a vertically disposed shaft 9 upon which a floating gear 11 is placed. This floating gear is adapted to be actuated back and forth by a rack 12 carried in slideways 13 and 14.

A cross-piece 16 serves to anchor one end of a spring 17, the opposite end of which is connected to a cable 18 which passes over a pulley 19 secured to the box-like structure 5 and has its opposite end secured to the rack bar 12 as shown at 21.

The opposite end of the rack bar has secured as at 22 a cable 23 which is passed over a pulley 24 and thence over a pulley 26 secured to the bottom of the box-like structure from which point the cable passes downwardly as shown at 27 and is then secured to a helical spring 28. The opposite end of this spring is connected by a rod 29 to a foot pedal 31 normally retained in elevated position by a spring 32. The pedal is preferably pivoted as at 33 to a base board 34.

A stop is shown at 36, which is braced by a rod 37, the purpose of which stop is to limit the movement of the rack bar 12 in one direction, while a similar stop 38 limits the movement of the rack bar 12 in the opposite direction.

Mounted upon the outer surface of the box-like structure 5 is a shaft 39. Upon this shaft 39 is rotatably positioned arm gears 41, 42, 43 and 44. These arm gears are mutilated in that the teeth extend only substantially one-third of the distance about the gear, as best shown in Figure 2.

These gears are spaced a suitable distance apart and each carries an arm 46 upon which clips 47 are positioned.

Referring now to Figure 4, it will be noted that a plurality of discs 48, 49, 51 and 52 are suitably spaced and joined together by spacer rods 53 and that these discs are mounted upon the shaft 9 to which they are secured as by a screw 54.

A ratchet is shown at 56, which is also secured to the shaft 9. This ratchet is adapted to be engaged by a spring-pressed dog

57 carried by the gear 11. The discs 48, 49, 51 and 52 are each provided with teeth as shown at 58, in Figure 1, which teeth extend around a portion of the periphery of each disc.

It will also be noted from this figure, that the teeth upon each disc are in staggered relation, the teeth extending substantially one-fifth of the distance about the disc. The result of this construction is that at one point when viewed from the top as shown in Figure 3, there is a space where no teeth appear. The purpose for this construction will be later seen.

15 At 59 I have shown a brake which rests upon the upper disc 48 and serves to prevent undue movement thereof. Secured to the underside of the box 5 is a bar 61 which is bent downwardly as shown at 62 and serves 20 to support a music rack of the usual construction which needs no further description.

The manner of operating my device is as follows:—

Assuming that the parts are in the position 25 shown in Figure 1, and that the music to be played is supported upon the rack in front of the device, the individual pages of the music will be engaged by the clips 47 carried on the arms 46. One page being clipped to 30 each arm.

By now pressing upon the pedal 31, a pull will be delivered to the cable 23 thus causing the rack bar 12 to move toward the left of the drawing. This movement toward the 35 left will actuate the gear 11 and through the dog 57, will actuate the ratchet 56 rotating the shaft 9 and the discs 48 to 52, inclusive. As soon as these discs start to rotate the teeth, the first disc 48 will engage the 40 teeth on the arm gear 41 thereby swinging the first arm from the position shown in Figure 3 around until the opposite side of the page is visible. As soon as this has been accomplished, the teeth on the gear 48 will 45 have cleared the teeth on the arm gear 41 and the release of the pedal will permit the rack 12 to return to its original position through the action of the spring 17 and through the fact that the gear 11 is floating upon the shaft

9, while the brake 59 will prevent retrograde 50 movement of the discs 48 to 52, inclusive.

A second actuation of the pedal will accomplish the same result, with the exception that the teeth upon the disc 49 will engage the teeth of the arm gear 42. The succeeding 55 operations will be identical.

After all of the pages have been turned, a point will be reached where no teeth are in alignment with the arm gears, and consequently the arms may be manually returned 60 to their original position.

It will thus be seen that I have provided a very simple means for effectively turning the leaves of books, music etc., with a minimum amount of effort upon the part of the 65 operator.

It is to be understood that the form of my invention herewith shown and described is to be taken as a preferred example of the same, and that various changes relative to 70 the shape, size, material and arrangement of parts may be resorted to without departing from the spirit of the invention, or the scope of the subjoined claim.

Having thus described my invention, I 75 claim:—

In a music leaf turner, a box-like structure, a shaft positioned within said structure, a floating gear positioned on said shaft, a ratchet secured to said shaft, a rack engaging 80 said floating gear and adapted to actuate said gear, a dog carried by said gear and engaging said ratchet, a plurality of spaced discs secured to said shaft, teeth formed upon a portion of the periphery of each of 85 said discs, a second shaft positioned parallel to said first mentioned shaft, mutilated gears positioned on said second mentioned shaft, and adapted to be engaged by the teeth of 90 said first mentioned discs, arms carried by 95 said mutilated gears and means for intermittently actuating said rack bar, said means including a tension device secured to one end of said rack bar for maintaining said rack bar in its normal position, and a cable extending to a remote point.

In testimony whereof I affix my signature.

WILHO E. LAITTI.
